UNITED STATES PATENT OFFICE

2,473,540

ELECTRICAL MOTOR AND DYNAMO BRUSH

Tobias Miller, Cleveland Heights, Ohio

Application February 26, 1944, Serial No. 524,015

2 Claims. (Cl. 171—325)

1

This invention relates to new and useful improvements in brushes for dynamos and motors of the types which are especially useful in unfavorable atmospheric conditions of moisture and temperature, as for example in connection with airplanes, dirigibles, and helicopters when flying at stratospheric heights.

The principal object of this invention is to provide motor and dynamo brushes with a protective jacket and insulation for protection from various climatic conditions, and for instance especially at stratospheric or such heights where low temperature tends to freeze the still remaining moisture absorbed in the lower atmosphere into small particles of ice which causes the compressed carbon brushes to crack and deteriorate, thus causing a dangerous condition and endangering flight of airplanes.

The same is hereby more fully described and claimed.

In the accompanying drawing, Figure 1 shows an armature *a* with insulated brushes *b* and connectors *c*.

Fig. 2 is a perspective view showing a brush *d* and a cellophane or plastic jacket *e* with wire *f* and connector *g*.

Fig. 3 is a sectional view showing a brush *i* with wire *h* imbedded therein and cellophane or plastic jacket *j* covering the entire brush with the exception of the surface *k* which is exposed toward the armature *a*.

The construction of my improved brush for motors and dynamos is best shown in said Fig. 3. The body *i* is composed of the usual material, e. g. compressed carbon, or its equivalent such as graphite, and to this body is applied a closely adhering plastic insulating jacket which completely encases such body save for the end face *k* thereof which is designed to contact with the commutator or other element of the machine with which electrical contact is to be made. As indicated, cellophane, i. e. amorphosed cellulose or precipitated cellulose, as from cellulose xanthate (Fieser's "Organic Chemistry," pages 892, 893, pub. by D. C. Heath & Co., Boston, 1944) or equivalent plastic material is preferably used to

constitute such protective coating. This material, as concisely summarized for instance under the heading "Cellophane" in Gardner's "Chemical Synonyms and Trade Names," pub. by D. Van Nostrand Co., New York, 1946, as a cellulose product obtained by precipitation, "is not affected by moisture or oils, is non-inflammable, and is insoluble in alcohol." The combination of this and a carbon body results in a brush which is thoroughly protected and which has an outstandingly firm tough surface not easily abraded or penetrated. Application of the coating to the body may be effected in any desired way, but preferably in liquid form, to insure close adherence and at least a certain degree of impregnation of the body by the plastic.

I claim:

1. An electrical contact member comprising a body of conducting material including compressed carbon, and a non-melting coating of amorphosed cellulose closely applied to the surface of such body.

2. An electrical contact member comprising a body of conducting material including compressed carbon, and a coating of amorphosed cellulose bonded onto such body except at one end.

TOBIAS MILLER.
